ATTORNEY

UNITED STATES PATENT OFFICE.

HARRY G. HOKE, OF STILLWATER, OKLAHOMA.

SWITCH MECHANISM.

Application filed June 16, 1922. Serial No. 568,676.

To all whom it may concern:

Be it known that I, HARRY G. HOKE, a citizen of the United States, and a resident of Stillwater, in the county of Payne and State 5 of Oklahoma, have invented a new and useful Improvement in Switch Mechanism, of which the following is a specification.

My invention relates to switch mechanisms and particularly to metal housings for containing switch and fuse devices employed in 10 electric circuits.

One object of my invention is to provide a standard switch housing with an auxiliary housing that is adapted to contain branch- 15 line fuses.

Another object of my invention is to provide a housing of the above character wherein the door for the auxiliary housing is so interlocked with the door for the switch housing that the door for the auxiliary housing can not be opened so long as the door for the 20 switch housing is in closed position.

Another object of my invention is to provide a housing, having the above characteristics, wherein the doors for both housings may be sealed in closed position by a single seal for preventing unauthorized persons from tampering or interfering with the apparatus contained therein.

Another object of my invention is to provide a housing of the above-described character, wherein the door for the switch housing cannot be closed without first closing the door for the auxiliary housing.

Another object of my invention is to provide a switch housing having integral flanges to which suitable attaching devices on an auxiliary housing may be applied for fastening the auxiliary housing to the switch housing without the use of screws or other separate fastening members.

A further object of my invention is to provide a housing for a switch and branch-circuit fuses that may be made of sheet metal 45 and which is simple and inexpensive to manufacture.

These and other objects, that will be made apparent throughout the further description of my invention, are attained by means of the switch mechanism hereinafter described, and illustrated in the accompanying drawings, wherein:

Figure 1 is a front view of the housings, showing the door for the switch housing 50 partially open, the door for the auxiliary housing being removed.

Fig. 2 is a longitudinal section through the housing taken on the broken line II—II of Fig. 1, and

Fig. 3 is an end view of the combined 60 switch and auxiliary housings.

Referring to the drawings, the apparatus includes a main switch housing 4, which is of standard construction, having inwardly-turned end flanges 5 to which ends plates 6 65 may be secured, as desired. The main housing is provided with a cover 7 that is attached to the housing by means of screws 8 that are threaded into clips 9 which are integral with the side walls of the housing. 70

A door 11, having side flanges 12 and an end flange 13, is pivoted to the housing by means of rivets 14 that extend through perforations in the side flanges 12 and the side flanges 15 of the cover 7, the side walls of 75 the housing being cut away, as at 16, to provide space for the rivet heads.

A switch panel 16^a is mounted within the housing 4 and supports fuse receptacles 17 and switch-jaw members 18 and 19. 80 Switch-blade members 21 are pivoted to the switch-jaw members 18 and are movable into contact with the contact-jaw members 19 by means of an operating rod 22. The switch-blade members 21 are connected by 85 means of an insulating bar 23 that is provided with a clip 24 through which an eyebolt 25 projects. The eyebolt 25 is pivoted to the operating rod 22 and is provided with a spring 26, that is disposed between the 90 clip 24, and a threaded nut 27 on the eyebolt.

The switch described is of standard construction and is provided with means for so interlocking the switch with the cover that 95 opening movement of the cover is precluded so long as the switch is in closed position and closing movement of the switch is prevented so long as the cover is in open position.

This interlock may be of any preferred 100 construction, for instance, such as that illustrated in the copending application Serial No. 324,811, filed Sept. 19, 1919 by Charles Cordier and assigned to the Westinghouse Electric & Manufacturing Com- 105 pany.

The switch-and-cover interlock comprises a plate 28 secured to the cover and having an arcuate flange 29 that engages an arcuate portion 30 of the switch-operating rod 22 110 when the switch is in closed position. When the switch is in open position, the portion 30

clears the flange 29 and permits opening movement of the cover. When the cover is open, the flange 29 lies across the path of movement of the bar 22 and prevents closing movement of the cover so long as the cover is in open position.

An auxiliary adaptor cabinet 33 is made of sheet metal and comprises integral side walls 34 and 35 and an end wall 36. The side walls are provided with inwardly turned flanges 37 and 38, the latter having integral tongues 39 extending therefrom that are bent in U shape and are adapted to slidably engage the flanges 5 of the side walls 15 of the housing 4.

The bottom of the cabinet 33 is provided also with an end flange 41 that is adapted to abut a similar flange 42 integral with the bottom of the housing 4. The side flanges 20 5 and 38 abut one another and constitute a closed seal between the housings.

A door 43 is pivotally mounted on the auxiliary housing by means of hinges 44 that are secured to the side wall 35 of the auxiliary housing. The door 43 is provided with side flanges 45 that overlap the side walls of the auxiliary housing and is also provided with an outwardly-extending flange 46 which is adapted to be overlapped by the 30 flange 13 of the door 11 when the latter is in closed position.

A clip 47 is secured to the flange 46 in such position that, when the cover 43 is in the open position indicated in Fig. 3, it lies 35 in the path of closing movement of the cover 11. It is apparent, therefore, that the cover 11 cannot be closed without first closing the door 43.

In order to limit the opening movement 40 of the cover 43 so that the clip 47 cannot be moved out of the path of closing movement of the door 11, a stop member 48 is attached to the underside of the door 43. The stop member 48 is provided with a stop web 49 45 that is adapted to engage a clip 51 secured to the end wall of the auxiliary housing, when the door 43 is moved to the open position shown in Fig. 3.

By reason of the construction illustrated 50 and above described, it will be seen that the door for the auxiliary housing cannot be opened so long as the door 11 for the switch housing is in closed position. It is also apparent that the door 11 cannot be opened so 55 long as the switch is in closed position and, therefore, access cannot be had to the device in the auxiliary housing so long as the switch is in closed position.

As illustrated in the drawings, a fuse 60 panel 52, having fuse receptacles 53 for two branch circuits, is mounted in the auxiliary housing 33, the fuses 54 in the receptacle 17 being the main service fuses. By reason of the adaptor housing, branch-line fuse receptacles may be associated with the entrance 65

switches usually enclosed in the standard safety housing, and, by reason of the interlock between the doors of the housing and between the door of the switch housing and the switch, the full safety feature of the main switch mechanism is extended to the fuses of the branch circuits. Access may not be had to the branch circuits so long as the switch is in closed position.

As an additional precaution against the 75 operator coming in contact with live parts, a barrier 55 is disposed within the main housing between the fuse receptacle 17 and the switch. When the doors are open, no live parts are accessible.

In order to render both compartments of the housing inaccessible to unauthorized persons, the flange 46 is provided with an extension 55 having a perforation 56. The extension projects through a slot 57 in the door 43 when the doors are in closed position and, consequently, both may be sealed in closed position by a seal 58 having its bail inserted through the perforation in the extension.

While I have illustrated and described 90 but one embodiment of my invention, it will be apparent to those skilled in the art that various changes, modifications, substitutions, additions and omissions may be made 95 therein without departing from the spirit and scope of my invention, as set forth in the appended claims.

I claim as my invention:

1. Switch mechanism comprising a housing, a cover for the housing, a movable door for the housing, a movable switch member in the housing, means for so interlocking the switch and the door that opening movement of the door is precluded so long as the switch is in closed position, an auxiliary 100 housing attached to the first housing and communicating therewith, a door for the auxiliary housing and means for preventing opening movement of the last said door so long as the switch is in closed position. 105

2. Switch mechanism comprising a housing, a cover for the housing, a movable door for the housing, a movable switch member in the housing, means for so interlocking the switch and the door that opening movement 110 of the door is precluded so long as the switch is in closed position, an auxiliary housing attached to the first housing and communicating therewith, a door for the auxiliary housing and means for preventing opening 115 movement of the last said door so long as the first said door is in closed position.

3. Switch mechanism comprising a housing, a cover for the housing, a movable door for the housing, a movable switch member 120 in the housing, means for so interlocking the switch and the door that opening movement of the door is precluded so long as the switch is in closed position, an auxiliary housing attached to the first housing and 125

communicating therewith, a door for the auxiliary housing having a flange overlapped by the first said door for preventing opening movement of the second door so long as the first door is in closed position.

4. Switch mechanism comprising a housing, a cover for the housing, a movable door for the housing, a movable switch member in the housing, means for so interlocking the switch and the door that closing movement of the switch is prevented so long as the door is in open position, an auxiliary housing attached to and communicating with the first housing, a second door for the auxiliary housing and means whereby the first door cannot be closed without closing the second door.

5. Switch mechanism comprising a housing, a cover for the housing, a door for the housing, switch mechanism within the housing, an auxiliary housing attached to and communicating with the first housing for containing branch line fuses, a door for the auxiliary housing and means for interlocking the doors whereby the second said door cannot be opened so long as the first door is in closed position.

6. Switch mechanism comprising a housing, a cover for the housing, a door for the housing, switch mechanism within the housing, an auxiliary housing attached to and communicating with the first housing for containing branch line fuses, a door for the auxiliary housing and means for interlocking the doors whereby closing of the first door causes closing of the second door.

7. The combination with a housing, having two doors hinged for rotation about different angularly disposed axes, one of the doors having a portion movable into the path of closing movement of the other door, of a means on the last said door for limiting its movement and preventing movement of the said means out of the path of closing movement of the other door.

8. A housing for electrical devices comprising a casing having separate compartments therein, separate doors for the said compartments, a switch in one compartment interlocked with one of the doors and means for so interlocking the doors that a single seal co-operating with the said means serves to retain the doors in closed position.

9. The combination with a switch, of an enclosure therefor having a closure member movable into and out of closing position, a cabinet associated therewith, said cabinet having a closure member movable into and out of closing position and means interlocking said closure members with said switch so

that said closure members can only be opened when said switch is in open circuit position.

10. The combination with a switch, of an enclosure therefor having a closure member movable into and out of closing position, a cabinet associated therewith, said cabinet having a closure member movable into and out of closing position and means interlocking said closure members with said switch so that said switch can only be closed when both said closure members are in closing position.

11. The combination with a switch, of an enclosure therefor, electrical devices in said enclosure, a closure member therefor, a cabinet associated therewith, electrical devices in said cabinet, and a closure member for said cabinet, said closure members being interlocked with said switch so that neither of said closure members can be opened to obtain access to said devices until after said switch has been opened.

12. The combination with a switch, of an enclosure therefor, a closure member for said enclosure, a cabinet associated therewith, a closure member for said cabinet, and means interlocking said closure members with each other and with said switch.

13. The combination with a switch, of an enclosure therefor, a closure member for said enclosure interlocked with said switch, a cabinet associated therewith and a closure member for said cabinet interlocked with said first closure member.

14. The combination with a switch, of an enclosure therefor, a closure member for said enclosure interlocked with said switch so that said closure member can be opened only when said switch is in open position, a cabinet associated therewith, a closure member for said cabinet, and means interlocking said last closure member and said first closure member so that said last mentioned closure member can be opened only after said first closure member is opened.

15. The combination with a switch, of an enclosure therefor, a closure member for said enclosure interlocked with said switch so that said switch can only be closed when said closure member is closed, a cabinet associated therewith, a closure member for said cabinet, and means interlocking said last closure member and said first closure member so that said first closure member can only be closed when said last closure member is closed.

In testimony whereof, I have hereunto subscribed my name this eighteenth day of May, 1922.

HARRY G. HOKE.
